REFINING OF MINERAL OILS

Barney R. Strickland, Roselle, N. J., assignor to
Standard Oil Development Company, a corpo-
ration of Delaware

Application December 26, 1940, Serial No. 371,670

3 Claims. (Cl. 260—627)

The present invention relates to the refining of mineral oils. The invention is more particularly concerned with the removal of objectionable sulfur-containing compounds and acidic constituents such as mercaptans and the like from petroleum oils and is especially concerned with the removal and recovery of naturally-occurring acidic oxygen-containing compounds. In accordance with the present process, these constituents are removed from petroleum oils and the quality of the same materially improved by utilizing a reagent selected from the class of alkali metal alcoholates.

It is known in the art to treat oils, particularly petroleum oils, in order to improve the quality of the same, utilizing numerous solvents and liquid reagents. It is also known in the art to remove mercaptan compounds and to recover naturally-occurring acidic oxygen-containing compounds such as naturally-occurring high molecular weight petroleum phenols and naphthenic acids. These operations employ various alkali solutions and solid reagents, such as oxides of aluminum, bauxite, silicates, silica gels, and the like.

I have, however, now discovered a process by which the quality of petroleum oil products may be improved and by which constituents which are undesirable in the same may be readily removed and recovered as valuable products. In accordance with my process, feed oils containing undesirable constituents, such as sulfur-containing compounds, mercaptans, naturally-occurring phenols, and naturally-occurring naphthenic acids are contacted with an alkali metal alcoholate under conditions adapted to remove the same.

The process of my invention may be readily understood by reference to the attached drawing illustrating modifications of the same. Figure 1 illustrates a solvent treating adaptation and modification of my invention utilizing a solvent comprising a solution of an alcoholate. Figure 2 illustrates a modification of my invention when distilling the feed oil to be treated over an alcoholic solution of the alcoholate, while Figure 3 illustrates another adaptation in which the oil being treated is distilled over a solid reagent.

Referring specifically to Figure 1, it is assumed that the feed oil is a petroleum oil boiling in the kerosene boiling range and that the reagent comprises a 15% to 20% solution of sodium methyl alcoholate dissolved in anhydrous methyl alcohol. The feed oil is introduced into the system by means of line 1 while the alcoholic solution of sodium methyl alcoholate is introduced by means of line 2. The mixture is passed through mixing zone 3 and introduced into zone 4 which may comprise any suitable number and

arrangement of units. In this zone the reactions comprise converting the mercaptans to mercaptides, the high molecular weight phenols to phenolates, and the high molecular weight naphthenic acids to naphthenates. Temperature and pressure conditions are adjusted to secure an oil phase and an alcoholic phase containing dissolved therein the mercaptans and acidic oxygen-containing constituents removed from the treated oil. The treated oil is withdrawn from zone 4 by means of line 5, and further refined or handled in any manner desirable. The alcoholic phase containing the mercaptides, the phenolates, and the naphthenates, is withdrawn from zone 4 by means of line 6 and passed into zone 1. Usually it is preferred to recycle at least a portion of the alcoholic solution until substantially the entire quantity of alcoholates is converted to the corresponding alcohol and salts by means of line 22. In zone 7, the alcoholic solution is subjected to temperature and pressure conditions adapted to remove overhead by means of line 8, substantially the entire amount of alcohol present. This alcohol may be removed from the system, but it is preferably combined with additional alcoholate and recycled. The bottoms product, comprising a slurry of alcohol, mercaptides, phenolates, and naphthenates, is removed from zone 7 by means of line 9, and diluted with a quantity of water which is introduced by means of line 12. The diluted mixture is introduced into zone 10 in which it is subjected to steam, which is introduced by means of line 11. Conditions are adjusted to remove overhead by means of line 13 the mercaptans regenerated from the corresponding mercaptides, and to remove as a bottoms by means of line 14, a caustic solution comprising phenolates and naphthenates. The overhead product removed by means of line 13, comprising mercaptans and steam, is condensed and passed into separation zone 23 in which a layer formation occurs. The mercaptans are withdrawn by means of line 24 while the water is removed by means of line 25. The bottoms, removed from zone 10 by means of line 14, is introduced into regeneration zone 26 in which phenols are regenerated from the corresponding phenolates. This is preferably secured by contacting the same with carbon dioxide, which is introduced by means of line 16. The phenols are separated as a separate layer and are removed by means of line 18. The lower layer, comprising naphthenates, is withdrawn by means of line 28 and further acidified under conditions to regenerate naphthenic acids from the corresponding naphthenates. This is preferably secured by the addition of a stronger acid which is introduced by means of line 27. When operating 60 in this manner, the naphthenic acids separate as

a separate layer in zone 20, and are removed by means of line 21, while the remaining constituents are removed by means of line 28.

Referring specifically to Figure 2, it is assumed that the feed oil containing mercaptans, phenols, and naphthenic acids is a petroleum oil boiling in the kerosene boiling range. For purposes of description, it is also assumed that the treating reagent is an essentially saturated solution of sodium methylate in methyl alcohol. The feed oil is introduced into the system by means of line 30, while the sodium methylate solution is introduced by means of line 31. The mixture passes through mixing zone 32 and is then introduced into distillation zone 33. Temperature and pressure conditions are adjusted to remove overhead, by means of line 34, the alcohol and the treated oil. The overhead stream is cooled in condenser 35 and passed into separation zone 36. The treated oil is condensed and separated from the alcohol by means of line 37. Uncondensed alcohol constituents are removed by means of line 38, and condensed and recycled through the system. The bottoms product removed from distillation zone 33, by means of line 39, is cooled in cooler 40 and mixed with a relatively small amount of alcohol which is introduced by means of line 41. The slurry, comprising a relatively small amount of high boiling oil constituents, mercaptides, phenolates, naphthenates, and the added alcohol, is introduced into separation zone 42. In separation zone 42 an oil phase separates from the alcoholic solution, and is removed by means of line 43. The alcoholic solution, comprising sodium mercaptides, phenolates, and naphthenates, is withdrawn from separation zone 42, by means of line 44, and introduced into zone 7 and handled in a manner described with respect to Figure 1, for the separation and segregation of the alcohol, the mercaptans, the phenols, and the naphthenic acid constituents.

Referring specifically to Figure 3, it is assumed that the feed oil is similar to that described with respect to Figure 2. The feed oil is introduced into the system by means of line 50 and mixed with a quantity of powdered solid sodium methylate, which is withdrawn from storage zone 52 and injected into the said oil by means of suitable conveying means 53. The mixture is passed through mixing and heating zone 54 and introduced into distillation zone 55. Temperature and pressure conditions are adjusted to remove overhead by means of line 56 the feed oil free of undesirable constituents. The overhead stream is condensed in condenser 57 and passed into distillation drum 58. Uncondensed gases are removed by means of line 59, while the treated distillate is removed by means of line 60 and further handled in any manner desirable. The bottoms product is removed by means of line 61, cooled in cooler 62, and combined with an appropriate small quantity of alcohol which is introduced into the system by means of line 63. The mixture, comprising phenolates, naphthenates, mercaptides, relatively high boiling oil constituents, and the added alcohol, is introduced into separation zone 64. The oily constituents separate as a separate layer and are withdrawn by means of line 65, while the alcoholic solution, comprising alcohol, mercaptides, phenolates, and naphthenates, is passed into zone 7 by means of line 66. This bottoms product is handled in a manner as described with

respect to Figure 1, in order to segregate the respective constituents.

The process of the present invention may be widely varied. Although the process may be employed for the treatment of any petroleum oil containing objectionable mercaptans, petroleum oil phenols, and naphthenic acids, it is particularly applicable in the treatment of petroleum oils boiling in the gas oil and kerosene boiling ranges. The process is especially desirable since it permits the recovery of relatively high boiling petroleum phenols, mercaptans, and naphthenic acids in an efficient and economical manner. These substances, due to their peculiar characteristics have heretofore been relatively difficult to segregate.

The reagents of the present invention are selected from the class of alkali metal alcoholates and are characterized by having a linkage RO—X, in which R represents an alkyl group and in which X is selected from the class consisting of sodium and potassium. Substances of this class are, for example, sodium methyl alcoholate, sodium ethyl alcoholate, sodium butyl alcoholate, potassium propyl alcoholate, potassium amyl alcoholate, polysodium glycerolate and the various alkali metal alcoholates of the polyhydroxy alcohols, such as sodium glycolate. The preferred reagents are the sodium alcoholates of the mono hydroxy alcohols, the constituents of which contain from 1 to 4 carbon atoms to the molecule.

The method of contacting the alcoholate and the petroleum oil will vary considerably and will in general depend upon the particular petroleum oil being treated and the particular alcoholate employed. Usually I prefer to contact the oil with an alcoholic solution of the alcoholate. Another preferred modification is to distill the oil over the reagent in the form of an alcoholic solution or in the form of a powdered solid. If an alcoholic solution be employed I prefer that the alcohol in which the alcoholate is dissolved be the alcohol from which the alcoholate was derived. Thus, for example, if sodium methylate be employed, it is preferred that the alcoholate be dissolved in methanol. If an alcoholic solution be employed, it is preferred that the concentration be in the general range of from 5 to 30%, preferably in the range from 10 to 20%.

The operating conditions likewise may be widely modified. Temperature and pressure may vary and will depend upon the particular feed oil being treated, the quantity and character of the phenols, mercaptans, and naphthenic acids present, as well as upon the particular alcoholate or alcoholate solution employed. Temperature and pressure conditions will also depend upon the feed rate and particle size of solid alcoholates be used. In general, when extracting the oil with an alcoholic alcoholate solution, it is preferred to employ atmospheric temperatures and pressures although temperatures in the general range of 30 to 150° F. may be employed in specific instances. If the feed oil be of a relatively high viscosity, it may be desired to employ heating means or to dilute the oil with an inert dilution solvent, as for example a relatively low boiling petroleum oil. The quantity of alcoholate solution used may be varied depending upon the concentration of the solution and the quantity of mercaptans, phenols, and naphthenic acids in the feed oil. Usually, 2 to 20% of reagent per volume of oil is preferred.

When distilling the feed oil over the alcoholate solid or solution, it is usually desirable to operate

at pressures below atmospheric and in the absence of steam or water. The quantity of alcoholate used should be a slight excess over the quantity theoretically required to neutralize the acid materials in the oil.

In order to further illustrate the present invention, the following examples are given which should not be construed as limiting the same in any manner whatsoever.

Example 1

A kerosene distillate containing approximately 0.2% phenols by weight was extracted in two stages with 2% by volume of a 30% solution of sodium methylate in methanol. The following data were obtained:

	Color, S.	Phenol No. ¹
Untreated kerosene	+20	200
Extracted with 2×2% of 30% NaOMe in MeOH	+27	1

¹ Phenol number is expressed as milligrams of t-amylophenol per 100 milliliters of oil.

It is apparent that sodium methylate is effective in removing phenols from feed oils.

Example 2

A heavy prime cut naphtha was extracted in two stages with 2% of a 30% solution of sodium methylate in methanol. The following data were obtained:

	S	Cu. No. ¹
Heavy P. C. naphtha Rerun over 1% of 30% NaOMe in MeOH (twice theoretical amount) with a maximum still temperature of 350° F.	Per cent 0.464 0.344	85. V. sl. sour.

¹ Copper number is expressed as milligrams of mercaptan sulfur per 100 milliliters of oil.

What I claim as new and wish to protect by Letters Patent is as follows:

1. A process for the recovery and segregation of naturally-occurring phenols, naphthenic acids and mercaptans from petroleum oil, which comprises contacting the oil with an alcoholic solution of an alkali metal alcoholate, separating the mixture into an oil phase and an extract phase containing the dissolved phenols, naphthenic acids and mercaptans, separately removing the oil and extract phases, distilling off the solvent from the extract phase, diluting the resulting product with water, stripping the aqueous mixture with steam to remove mercaptans, reacting the stripped product with carbon dioxide to liberate phenols which are drawn off, and acidifying the residue to separate naphthenic acids.
- 5 2. A process for the recovery and segregation of naturally-occurring phenols, naphthenic acids and mercaptans from petroleum oil, which comprises contacting the oil with an alcoholic solution of an alkali metal alcoholate, distilling off the alcohol and oil from the alcoholate, condensing the oil, recycling the alcohol to the contacting step, diluting the still residue with water, stripping the aqueous mixture with steam to remove mercaptans, reacting the stripped product with carbon dioxide to liberate phenols which are drawn off, and acidifying the residue to separate naphthenic acids.
- 10 3. A process for the recovery and segregation of naturally-occurring phenols, naphthenic acids and mercaptans from petroleum oil, which comprises contacting the oil with a powdered solid alkali metal alcoholate, distilling the oil from the alcoholate, extracting the still residue with a small amount of alcohol to remove occluded oil, distilling off the alcohol from the oil-free product, diluting the resulting product with water, stripping the aqueous mixture with steam to remove mercaptans, reacting the stripped product with carbon dioxide to liberate phenols which are drawn off, and acidifying the residue to separate naphthenic acids.
